US00D865438S

(12) **United States Design Patent** (10) Patent No.: **US D865,438 S**
(45) Date of Patent: **** Nov. 5, 2019**

(54) **BLENDER BASE**

(71) Applicant: **SharkNinja Operating LLC**, Needham, MA (US)
(72) Inventors: **Devin Coakley**, Bellingham, MA (US); **Christopher Gidwell**, Sherborn, MA (US); **Cory R. Smith**, Auburndale, MA (US); **Joyce Tu**, Arlington, MA (US)
(73) Assignee: **SHARKNINJA OPERATING LLC**, Needham, MA (US)
(**) Term: **15 Years**
(21) Appl. No.: **29/685,512**
(22) Filed: **Mar. 28, 2019**

Related U.S. Application Data

(60) Division of application No. 29/653,896, filed on Jun. 19, 2018, now Pat. No. Des. 847,559, which is a division of application No. 29/604,189, filed on May 16, 2017, now Pat. No. Des. 823,637, which is a division of application No. 29/531,840, filed on Jun. 30, 2015, now Pat. No. Des. 795,005, which is a continuation of application No. 29/519,682, filed on Mar. 6, 2015, now Pat. No. Des. 793,153.

CLAIM

The ornamental design for a blender base, as shown and described.

DESCRIPTION

FIG. 1 is a perspective view of an embodiment of a blender base showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
